5 Claims. (Cl. 206—57)

ABSTRACT OF THE DISCLOSURE

A bag unit comprising a pair of bag pockets that are integrally connected to opposite side edges of a spacer strip by means of interrupted slits, the interruptions in the slits acting as tearable connecting means. When the bags are torn away from the spacer strip on the slotted lines, the slits define open mouths on the bags. The bags are individually removable from the spacer strip so that the spacer strip can act as a permanent backer in a holder. In this manner, a plurality of overfolded and overlapped bag units can be mounted on a support and thereby constitute a unitary package or assembly from which individual bags can be removed in completed form whenever desired.

This invention relates to plastic bags, and it particularly relates to an improved process for the manufacture of such bags.

Plastic bags, made of polyethylene, polypropylene or similar thermoplastic polyolefins are today used for many packaging purposes not only in the home but in retail businesses as well as in industry. These bags are becoming increasingly popular not only because they are highly air and moisture proof and easy to use but because they are relatively inexpensive and can be easily mass-produced. However, this very fact makes it important to achieve the greatest economy possible in their manufacture since the saving of even a fraction of a cent per bag results in large savings because of the great number of bags produced.

The large volume of sales of these bags makes for a highly competitive market and, therefore, even a seemingly small saving in the cost of manufacture results in a great competitive advantage.

It is the primary object of the present invention to provide a method and apparatus for making polyolefin bags which results in substantial saving in time and labor and therefore in the ultimate cost of the bags.

Another object of the present invention is to provide packaged units of bags which are specially adapted to the aforesaid method of manufacture whereby the packaged units themselves provide the final step of making the bags, this final step being performed by the consumer.

Other objects and many of the attendant advantages of this invention will be readily appreciated as the same becomes better understood by reference to the following description when read in conjunction with the accompanying drawings wherein:

FIG. 1 is a somewhat diagrammatic, fragmentary view showing a tubular strip of polyolefin material being processed to form bag units.

FIG. 2 is a perspective view of a single bag unit after being folded and prior to being combined with other similar bag units to form a package unit.

FIG. 3 is a perspective view of a package unit comprising a plurality of bag units such as shown in FIG. 2.

FIG. 4 is a fragmentary perspective view of a package unit, such as shown in FIG. 3, releasably connected to a supporting hanger.

FIG. 5 is a perspective view of a finished bag after it has been removed from the package unit shown in FIGS. 3 and 4.

2

FIG. 6 is a view similar to FIG. 1 but showing the manufacture of a different type bag.

FIG. 7 is a view similar to FIG. 2 but showing a bag unit made by the process illustrated in FIG. 6.

5 FIG. 8 is a view similar to FIG. 3 but showing a package unit containing the bag units of FIG. 7.

FIG. 9 is a somewhat diagrammatic view of a process of making yet another type of bag.

10 FIG. 10 is a perspective view of a package unit made up of bags formed in the process illustrated in FIG. 9.

FIG. 11 is a perspective exploded view of a preferred method of packaging the bags.

15 Referring now in greater detail to the various figures of the drawings wherein similar reference characters refer to similar parts, there is shown in FIG. 1 a tubular strip 10 of a thermoplastic polyolefin such as polyethylene or polypropylene. This strip 10 is shown as it is passed through a bag making machine. The machine itself is not illustrated since it may be any one of a number of standard machines wherein a heated sealing and cutting head is intermittently applied to the strip as the strip is passed longitudinally through the machine. The heated head, here shown diagrammatically and designated 12, passes transversely through the thermoplastic strip 10 and simultaneously severs a portion thereof and heat-seals the severed edge.

20 In the present method, however, prior to application of the heated head 12, the strip 10 is scored longitudinally by a double line of scoring along its center, these lines of scoring being illustrated at 14 and 16. This scoring can be accomplished in any manner desired, such as by providing appropriate cutting means on the machine, or by cutting the strip manually, or by pre-scoring the strip prior to its insertion in the machine, etc.

25 The slits in the lines 14 and 16 are identical to each other, each line consisting of alternate relatively short and long slits, so that each long slit is bounded on either end by a short slit. The slits in each line are closely spaced from each other so that only small uncut spaces or nips are provided therebetween.

30 The head 12 is operated in conjunction with the longitudinal movement of the strip 10 so that it is applied to the strip midway between each parallel pair of small slits in the lines 14 and 16, as shown in FIG. 1. This results in the severing of a bag unit, such as shown at 18.

35 The bag unit 18, as it comes from the strip, actually consists of two identical portions 20 and 22. Each portion is sealed on three sides due to the fact that the unit is formed from tubular material so that the ends are closed, while the sides are sealed by the heated head 12. On the fourth, or inner side, each portion is defined by a slotted edge, respectively designated 24 and 26. These slotted edges are separated from each other by a spacer portion 28. The slotted edges 24 and 26 form open ends except for the nips 30 and 32 respectively. These nips keep the two portions 20 and 22 connected to each other.

40 The bag units 18 are then separately folded along the longitudinal center of the spacer portion 28, as shown in FIG. 2. Reinforcements, shown at 34, are then applied to the spacer portion 28, one adjacent each nip 30 and 32.

45 The reinforcements extend through the folded spacer portion so that each provides a reinforcement for a corresponding pair of nips 30 and 32. These reinforcements are preferably welds formed in the thermoplastic material itself, but may also take the form of staples, cords, plastic or rubber strips, or any other feasible means.

50 A number of the bag units shown in FIG. 2 are then overfolded, one over the other, and a backer 36 is secured around the spacer portions (as shown in FIG. 3) to form a package unit 38. Staples, welds or the like, shown at 40, are used to fasten the backer 36 in place.

The package unit 38 can be used in any manner desired. One preferred manner is to removably secure it to a hanger, such as shown at 42 in FIG. 4. This hanger 42 may be constructed of metal, plastic, wood or any other desirable, relatively rigid material, and is secured on a wall or other supporting surface by any desirable means such as adhesive, screws, nails, rivets, etc. The hanger has a hook portion 44 and the package unit 38 is secured to the hanger by passing the mating center portions of the slits 24 and 26 over the hook portion 44 in the manner shown in FIG. 4.

While the bag units 18 remain in the package units 38, the bags, as such, do not yet exist. However, when a bag is desired, the outer bag unit portion 20 or 22 is grasped and pulled away from the package. This breaks the nips 30 or 32 and what is pulled away is a complete bag 46, shown in FIG. 5.

In the above manner, two bags, each constituting one portion of unit 18, are formed simultaneously and with a single motion of the sealing and severing head 12. At the same time, the two bags are held together so that they are more easily handled and packaged than individual bags. Furthermore, they are so connected that they are easily dispensed when packaged.

The bags formed by the method described above have an open end defined by a pair of edges in the same plane. Although such bags are efficient for all their purposes, it is sometimes desirable to have a bag that is provided with a lip at its open end to permit easy grasping both for pulling the bag away from the package unit and for opening the bag itself. Such a lip is provided by making one edge at the open end lower than the other.

The present method can be used for making bags with lips as illustrated in FIGS. 6, 7 and 8. In FIG. 6, there is shown a tubular strip 50 that is provided with a longitudinally extending slot 52 at its center. The slot 52, which is defined by oppositely-disposed straight parallel edges, is provided only on the upper surface 54 of the tubular strip, the bottom surface 56 being uncut. This slot 52 may be pre-formed in the tubular stock or it may be obtained by providing knife means on the machine or it may even be formed by hand with a razor edge or the like.

The tubular strip 50, with the slot 52 in its upper surface, is then treated in the same manner as the strip in FIG. 1, except that the lines of scoring, indicated at 58 and 59, are impressed only in the bottom surface framed and within the longitudinal slot 52. The heated severing and sealing head 60 is similar to the head 12 and similarly severs a bag unit 62 with each stroke.

The bag unit 62 comprises two bag portions 64 and 66, each of which has an inner edge, as at 68 and 70 respectively, that stops short of the respective score lines 72 and 74. These score lines later form the edge of the rear walls of the bags.

The bag unit 62 is then folded, as in FIG. 7, similarly to the bag unit 18. However, in this case, only the rear wall 56 serves as the hinge means. A reinforcement 75 such as a weld, staple, or the like, is provided adjacent each nip in the score lines, similarly to those shown in FIG. 2.

A number of bag units 62 are then overfolded one over the other and provided with a backer 76 similar to the backer 36 shown in FIG. 4, the resulting package unit being designated 78.

The above process has been described with particular relation to the manufacture of relatively small bags, each having a length of approximately half the width of the tubular strip. However, this process can also be advantageously used in the manufacture of larger bags having a length approximately equal to the width of the tube. This is illustrated in FIGS. 9 and 10 where the tubular strip 80 is provided with a single line of scoring adjacent one edge. This line of scoring, designated 82, is similar to each line of scoring shown in FIGS. 1 and 6 in that it comprises alternative large and small slits.

The scored tube 80 is passed under a heated severing and sealing head 84 similar to those shown at 12 and 60. The head 84 severs a bag unit 86 having an openable end defined by the score line 88.

5 A number of bag units 86 are then assembled, one adjacent the other, into a package unit 90 having a backer 92 similar to those shown at 36 and 72.

It is apparent that, if desired, the score lines, such as shown at 14 and 16, may be off-center relative to the longitudinal axis of the tube so that one operation can result in bags of different sizes. Furthermore, more than one pair of score lines, such as shown at 14 and 16, can be provided, whereby more than two bags can be made in each operation of the head 12.

10 15 Any of the package units described above may be inserted in a paper bag or the like constituting a wrapper, and the backer portion stapled or otherwise secured to one end of the wrapper bag. A score line may then be provided around the wrapper bag to separate the bottom portion

20 25 thereof from the upper portion to which the backer is secured. This bottom portion may then be removed by the consumer leaving the lower portions of the bag unit available for grasping. This is illustrated in FIG. 11 where there is shown a package unit 100 positioned within a wrapper bag having an upper portion 102 and a removable lower portion 104. The backer portion of the package unit 100 is stapled, as at 106, or otherwise secured, to the inside of the upper portion 102.

The lower portion 104 is secured to the upper portion 30 30 102 by a score line and is removable therefrom by merely tearing around the score line.

35 Obviously, many modifications of the present invention are possible in the light of the above teachings. It is, therefore, to be understood that within the scope of the appended claims, the invention may be practiced otherwise than as specifically described.

The invention claimed is:

1. A bag unit comprising at least one pair of pockets, each pocket being defined by a front wall and a rear wall 40 that are sealingly connected around the entire periphery of the pocket except at a mouth portion thereof, the mouth portion of each pocket being defined by an interrupted slit having at least one interruption, forming a nip, intermediate its ends, the interrupted slits of said pockets being 45 in opposed positions relative to each other and being separated from each other by a spacer portion, said spacer portion being integrally connected to each of said pockets by said nips, said mouth portions of the pockets being completely open and unsealed except for said nips, and 50 said spacer portion being substantially imperforate between its edges defined by said interrupted slits.

2. The bag unit of claim 1 wherein reinforcements are provided in said spacer portion adjacent each nip.

3. The bag unit of claim 1 wherein said spacer portion 55 is provided with a longitudinal fold line forming a hinge upon which the bag portions are overfolded on each other, said spacer portion constituting a base portion and said bag portions being separable therefrom by breaking said nips.

60 4. The bag unit of claim 1 combined with a plurality of other similar bag units to form a package unit, the spacer portions of the bag units being overlapped to form a base portion for said package unit, and a wrapper bag enclosing said package unit, said wrapper bag having an upper and a lower portion, said portions being removably connected to each other, and said base portion being secured to said upper portion of said wrapper bag.

5. The bag unit of claim 1 combined with a plurality 70 of other similar bag units to form a package unit, the spacer portions of the bag units being overlapped to form a base portion for said package unit, and the score lines of the bag units mating with each other to form a common slot.
